Inventor:
Johann Kamps
4/20/27

UNITED STATES PATENT OFFICE.

JOHANN KAMPS, OF DISLAKEN-EPPINKHOVEN, GERMANY.

STATIONARY COWL WITH WIND CHANNELS.

Application filed August 20, 1927, Serial No 214,414, and in Germany January 28, 1927.

Cowls composed of single profiled bricks and having air-injecting channels exerting a suction-effect upon the smoke channel, have become known. In all these arrangements 5 the air-injecting channels are constructed so that they taper towards the interior of the chimney in ascending at the same time from below upwards so that the wind entering from the outer side is deflected in the direction of the air or smoke-current ascending in the chimney whereby the velocity of the wind is increased in accordance with the 10 tapering of the channels, so that a suction-effect is exerted upon the air or smoke-current. It has further become known to absolutely prevent any penetration of air-currents into the chimney from above downwards, in utilizing wind coming from any 15 direction whatsoever for accelerating the air-draught, the mouth of the chimney being covered by a special lid and the end of the chimney being of special shape so that it forms the wind channels together with the 20 cowl.

From these cowls of known type the cowl according to the invention differs, as it is not built from several building-elements but made in one piece with the chimney, the air-injecting channels being constructed so that 25 they extend over the entire inner width of the smoke-channel, are more or less S-shaped in the direction from below upwards, and taper towards the middle, so that the entrance-orifice and the end communicating 30 with the smoke-channel are of similar cross section, the outlet orifices of the air injecting channels forming a continuation of the outlet of the smoke channel. By this arrangement wind currents entering the top of the 35 cowl find exit downwardly thru the air injecting channels at the lee side and produce

a suction effect on the smoke channel, so that wind currents from any direction are utilized to exhaust the smoke. The improved arrangement of the air injecting channels has 45 further the advantage, that access of rain is practically prevented without any covering of the smoke-channel. This is possible owing to the fact that the air-channels extend over the entire inner width of the smoke- 50 channel. The rain does generally not come down vertically but mostly, owing to the wind, at a certain angle.

An embodiment of the invention is shown, by way of example, in the accompanying 55 drawing, in which

Fig. 1 is a vertical central section through the cowl.

Fig. 2 is a top plan view of Fig. 1.

The cowl *a*, of any desired cross section, 60 has four opposite channels *b* extending each over the same width and at the orifice of the smoke-channel *c* over the entire inner width of the same. The channels *b* are curved more or less in S-shape, the inner orifice *d* 65 being of the same width as the outer orifice *e*, the channel *b* which connects these two orifices tapering from both ends inwardly towards the middle.

I claim:—

A stationary cowl formed integral with a chimney, said cowl having inwardly and upwardly extending wind-channels extending therethrough, the outer and inner orifice of each channel being of the same width, each 75 channel being substantially S-shaped and tapering uniformly from both ends toward the middle and having uniform width co-extensive with the width of the smoke channel.

In testimony whereof I affix my signature.

JOHANN KAMPS.
